TRAVEL TRAILER

Georges Etienne Christin, Marnes-la-Coquette, France,
assignor to Etablissements Bertrand Faure, Puteaux,
France, a corporation of France

Filed Mar. 17, 1966, Ser. No. 1,512

Claims priority, application France Sept. 30, 1965

Term of patent 14 years

(Cl. D14—3)

Fig. 1

FIGURE 1 is a perspective view of a travel trailer embodying my new design with the end closures in their opened condition;

FIGURE 3 is a top plan view of said travel trailer with the end closures thereof in their closed condition;

The dominant features of the design are shown in solid lines.

I claim:

The ornamental design for a travel trailer, as shown and described.
